(57) **CLAIM**

The ornamental design for a writing instrument, as shown and described.

DESCRIPTION

FIG. 1 is a left side view showing our new design for a writing instrument;

FIG. 2 is a rear view of the writing instrument of FIG. 1;
FIG. 3 is a front view of the writing instrument of FIG. 1;
FIG. 4 is a left side view of the writing instrument of FIG. 1 showing an alternative position for a rotatable section of the shaft, the opposite side view being a mirror image thereof;

FIG. 5 is a top plan view of the writing instrument of FIG. 1;

FIG. 6 is a top plan view of the writing instrument of FIG. 4;

FIG. 7 is a bottom plan view of the writing instrument of FIG. 1;

FIG. 8 is a front view of a second embodiment of our new design;

FIG. 9 is a left side view of the writing instrument of FIG. 8, the opposite side view being a mirror image thereof;

FIG. 10 is a top plan view of the writing instrument of FIG. 8;

FIG. 11 is a bottom plan view of the writing instrument of FIG. 8;

FIG. 12 is a left side view of a third embodiment of our new design;

FIG. 13 is a rear view of the writing instrument of FIG. 12;

FIG. 14 is a front view of the writing instrument of FIG. 12;

FIG. 15 is a left side view of the writing instrument of FIG. 12 showing an alternative position for a rotatable section of the shaft, the opposite side view being a mirror image thereof;

FIG. 16 is a top plan view of the writing instrument of FIG. 12;

FIG. 17 is a top plan view of the writing instrument of FIG. 15;

FIG. 18 is a bottom plan view of the writing instrument of FIG. 12;

FIG. 19 is a left side view showing a fourth embodiment of our new design;

FIG. 20 is a rear view of the writing instrument of FIG. 19; FIG. 21 is a front view of the writing instrument of FIG. 19;

FIG. 22 is a left side view of the writing instrument of FIG. 19 showing an alternative position for a rotatable section of the shaft, the opposite side view being a mirror image thereof;

FIG. 23 is a top plan view of the writing instrument of FIG. 19;

FIG. 24 is a top plan view of the writing instrument of FIG. 22;

FIG. 25 is a bottom plan view of the writing instrument of FIG. 19;

FIG. 26 is a left side view of a fifth embodiment of our new design;

FIG. 27 is a rear view of the writing instrument of FIG. 26; FIG. 28 is a front view of the writing instrument of FIG. 26;

FIG. 29 is a left side view of the writing instrument of FIG. 26 showing an alternative position for a rotatable section of the shaft, the opposite side view being a mirror image thereof;

FIG. 30 is a top plan view of the writing instrument of FIG. 26;

FIG. 31 is a top plan view of the writing instrument of FIG. 29; and,

FIG. 32 is a bottom plan view of the writing instrument of FIG. 26;

The dashed lines are for illustrative purposes only and form no part of the claimed design.
